(57) **CLAIM**

The ornamental design for a vehicle bumper, as shown and described.

DESCRIPTION

FIG. 1 is a top, front, right-side perspective view of a vehicle bumper;

FIG. 2 is a bottom, front, left-side perspective view thereof;

FIG. 3 is a front view thereof;

FIG. 4 is a right-side view thereof. The left-side view is a mirror image of the right-side view;

FIG. 5 is a top view thereof;

FIG. 6 is a bottom view thereof;

FIG. 7 is a top, front, right-side perspective view of a vehicle bumper including removable environmental context shown in broken lines;

FIG. 8 is a bottom, front, left-side perspective view thereof;

FIG. 9 is a front view thereof;

FIG. 10 is a right-side view thereof. The left-side view is a mirror image of the right-side view;

FIG. 11 is a top view thereof; and,

FIG. 12 is a bottom view thereof.

The dashed broken lines depict portions of the vehicle bumper and environmental context of the vehicle bumper that form no part of the claimed design.

1 Claim, 12 Drawing Sheets
